CLAIM

The ornamental design for a telephone with a holder, as shown and described.

DESCRIPTION

FIG. 1 is a top perspective view of a telephone with a holder showing our new design;

FIG. 2 is a front elevational view thereof;

FIG. 3 is a rear elevational view thereof;

FIG. 4 is a side elevational view thereof;

FIG. 5 is a right side elevational view thereof;

FIG. 6 is a top plan view thereof;

FIG. 7 is a bottom plan view thereof;

FIG. 8 is a top perspective view of the receiver;

FIG. 9 is a front elevational view thereof;

FIG. 10 is a side elevational view thereof, the other side being identical;

FIG. 11 is a rear elevational view thereof;

FIG. 12 is a bottom plan view thereof;

FIG. 13 is a top plan view thereof;

FIG. 14 is a top perspective view of the holder; and,

FIG. 15 is a front elevational view thereof.

The phone cord has been shown broken away in FIGS. 1-7 and the receiver and holder have been shown separately in FIGS. 8-15 for convenience of illustration.
